PLASTER TERMINAL

Filed Sept. 12, 1927

Witness:

R. S. Gidron

Inventor
Isaac A. Baum
By *Chas J. Murphy, Atty*

UNITED STATES PATENT OFFICE.

ISAAC A. BAUM, OF CHICAGO, ILLINOIS.

PLASTER TERMINAL.

Application filed September 12, 1927. Serial No. 219,094.

My invention relates to plaster terminals and particularly to metal plaster terminals that provide a bracing feature.

It is well known that one of the greatest objections to the common forms of plaster terminals is lack of rigidity in contact with the rough buck. When the building is under construction, materials are necessarily brought in through unfinished doors and windows with the result that blows of various degrees of severity are brought to bear upon the corners where the plaster extends.

However, the plaster terminal of my invention is intended to prevent the liability of injury to plaster at corners during construction, and in addition, to provide a most rigid construction at the corner.

My invention consists of a relatively long, narrow, strip of sheet metal, bent into several angles to provide spaced legs for contact with the wide face of a rough buck, a plaster defining portion having a plurality of apertures to provide plaster anchors, and another portion acting as a base, which is intended to lie at right angles to the legs and contact the narrow face of the rough buck.

The invention herein contemplated will be more readily understood by reference to the accompanying drawing, in which;

Fig. 1 is a perspective view of a device constructed in accordance with my invention, fitted to a rough buck;

Fig. 2 illustrates a modified form of my invention.

By reference to the drawing, and referring particularly to Fig. 1, it will be seen that I have illustrated a rough buck, A, plaster B and door jamb and stop, C. The device of my invention comprises legs 10 cut out of the metal and spaced at intervals along the length of the strip for a purpose to be later described, a plaster defining portion 11, terminating in a bead 12 which is bent back on itself to contact the portion 11, then bent diagonally backward, and then outward, to provide the base member 13. The base member 13 lies in a plane at right angles to the plane of the legs 10 and plaster defining portion 11. Ears 14 are cut out from the metal of the diagonal portion, which ears are adapted to lie as an extension of the base 13 and at their ends to be bent at right angles at their intersection with the inner face of the plaster defining portion 11. The ears 14 are suitably secured by welding or riveting, to the plaster

defining portion 11. The remaining metal of the diagonal portion acts as a brace for the plaster-defining portion and insures rigidity at all times.

Thus it will be seen that by securing the ears 14 to the portion 11, the corner angle is maintained as a right angle and a snug fit with a rough buck is insured. Apertures 15, 16 are provided as nail holes for securing the device to the rough buck. The plaster entering the openings left by cutting out the ears, 14, will provide an excellent plaster anchor. It is evident, therefore, that by the construction here illustrated, an extreme degree of rigidity, firm contact with the rough buck, and a firm plaster anchor, are all insured.

In Fig. 2, I have illustrated a modified form of my invention. The parts are essentially the same with the exception of the provision of the ears 14 in Fig. 1. Lateral slots 17 are provided in the inner face of the plaster defining portion to serve as plaster anchors. In place thereof the contacting parts of the base 13, and flange 11 are welded as indicated at 11^a in Fig. 2. The device illustrated in Fig. 2 is more economical to manufacture, but lacks a certain degree of rigidity obtained in the first described terminal.

The cutting away of the metal between the legs 10 serves a very useful purpose. After the plaster terminal is set up and securely fastened to the rough buck, the door jamb and stop is set in place. It is usually necessary to line up and straighten the jamb by means of various wedges driven between the jamb and buck from one side. If the metal were not cut away, the wedges would be likely to contact the edge of the plaster terminal. The workman may very easily insert his wedges between the ears without disturbing the terminal.

The device here illustrated may be manufactured in any lengths, or may be cut to required lengths on the job. The strip is economically manufactured, easily shipped and is capable of the highest efficiency in operation.

Obviously this device may be used with equal efficiency adjacent to a window opening, and I do not intend to limit myself to the application of this device in connection with a door frame.

Modifications and variations may be made in the invention here described within the skill of the mechanic, and I do not wish to

be limited except as indicated in the appended claims.

I claim:

1. In a device of the class described, a long, relatively narrow, strip of sheet metal, bent to provide right angularly disposed portions, said portions being adapted to contact two faces of a wood corner brace, a plaster defining portion formed in one of said right angularly disposed portions, said plaster defining portion being bent diagonally backward and terminating in said other right angularly disposed portion, and means for securing said right angularly disposed portions at the intersection of the angle thereof.
2. A plaster terminal comprising a strip of metal bent to provide right angularly disposed portions adapted to lie on two adjacent sides of a wood frame member, one of said right angularly disposed portions comprising a plurality of spaced legs, an intervening plaster defining portion extending the length of said strip, a plaster bead formed on the margin of said plaster defining portion

by bending the metal thereof, a portion extending diagonally from said bead back to said right angularly disposed portion, and means for securing the said right angularly disposed portions at the intersection thereof.

3. A plaster terminal comprising a strip of metal bent to provide right angularly disposed portions adapted to lie on two adjacent sides of a wood frame member, one of said right angularly disposed portions comprising a plurality of spaced legs, an intervening plaster defining portion extending the length of said strip, a plaster bead formed on the margin of said plaster defining portion by bending the metal thereof, a portion extending diagonally from said bead back to said right angularly disposed portion, said diagonally disposed portion being provided with a plurality of spaced apertures, and means for securing the said angularly disposed portions at the intersection thereof.

In testimony whereof I have affixed my signature.

ISAAC A. BAUM.
